Primary Examiner — Eric L Goodman*Assistant Examiner* — Amy C Wierenga(74) **Attorney, Agent, or Firm:** Erickson Law Group, PC(57) **CLAIM**

The ornamental design for a strainer device for a drain, as shown and described.

DESCRIPTION

FIG. 1 is a perspective view of a strainer device for a drain, showing our new invention;
 FIG. 2 is a front view thereof;
 FIG. 3 is a rear view thereof;
 FIG. 4 is a right side view thereof;
 FIG. 5 is a left side view thereof;
 FIG. 6 is a top view thereof; and,
 FIG. 7 is a bottom view thereof.
